United States Patent Office

Des. 202,584
Patented Oct. 19, 1965

202,584

TYPEWRITER

Chester J. Abend, Camillus, and William A. Morrison,
Syracuse, N.Y., assignors to SCM Corporation, New
York, N.Y., a corporation of New York

Filed May 11, 1964, Ser. No. 79,916

Term of patent 14 years

(Cl. D64—11)

Fig. 1

Fig. 2

FIG. 3

FIG. 4

FIG. 5

FIGURE 1 is a front perspective view of a typewriter showing our new design.

FIGURE 2 is a top plan view thereof;

FIGURE 3 is a front elevational view;

FIGURE 4 is a left side elevational view; and

FIGURE 5 is a rear elevational view thereof.

The dominant features of our design reside in those portions shown in solid lines in the drawing.

We claim:

The ornamental design for a typewriter substantially as shown and described.
